[57] CLAIM

The ornamental design for a bottle, substantially as shown.

DESCRIPTION

FIG. 1 is a perspective view of a bottle showing our new design;

FIG. 2 is a face elevational view.

FIG. 3 is a side elevational view.

FIG. 4 is a plan view.

FIG. 5 is a bottom view.

FIG. 6 is an elevational view of the face opposite to that of FIG. 2.

FIG. 7 is a vertical sectional view taken along line 7—7 of FIG. 4.

FIG. 4FIG. 5
